UNITED STATES PATENT OFFICE.

LLEWELLYN HENRY, OF CINCINNATI, AND JAMES O. TEBOW, OF ELIZABETHTOWN, OHIO.

BICYCLE-HUB.

SPECIFICATION forming part of Letters Patent No. 582,861, dated May 18, 1897.

Application filed September 10, 1896. Serial No. 605,394. (No model.)

To all whom it may concern:

Be it known that we, LLEWELLYN HENRY, residing at Cincinnati, and JAMES O. TEBOW, residing at Elizabethtown, county of Hamilton, State of Ohio, have invented certain new and useful Improvements in Bicycle-Hubs, of which the following is a specification.

The object of our invention is to so construct the hub and ball-bearings of a bicycle-wheel that the ball-bearings can be adjusted without disturbing the ball-bearing supports and secured in any desired adjustment by clamp-nuts.

Another object of our invention is to so construct the hub that the wheel can be removed from the axle and frame forks without disturbing the ball-bearings.

The features of our invention are more fully set forth in the description of the accompanying drawings, making a part of this specification, in which—

Figure 1 is a longitudinal vertical section of our improvement, showing the frame and clamp mechanism in elevation. Fig. 2 is a sectional end view on line *v v*, Fig. 1, with the packing-ring removed. Fig. 3 is a perspective view of the inner face of the packing-ring. Fig. 4 is a reverse face view of Fig. 3.

A represents the shell of the hub; B, the spoke-disks.

C represents an outward end extension of the shell A. There is also a slight inward extension of the shell A at a point about opposite the spoke-disks, which forms with the extension C a socket for the reception of cups D, which may be simply seated therein or screw-threaded, as desired. The concave inner surfaces of said cups form the outer ball-bearing support. E represents a sleeve which passes transversely through the shell and forms a housing for the axle. The outer ends of said sleeve are screw-threaded.

F represents cones which are screw-threaded upon the ends of the sleeve E. The inner faces of said cones are concave and form the inner ball-bearing support. H represents set-nuts tapped on the outer ends of said sleeve to hold the parts to any desired adjustment.

h represents washers interposed between the nuts H and the cones F. The said sleeve

E projects through the set-nut H a sufficient distance to form a shoulder, against which the frame-forks are clamped by means of nuts I I'. In order to prevent dust from working in between the parts, we provide packing-rings K, which are recessed on their inner faces and have screw-threads on their outer surfaces engaging with screw-threads on the inner faces of the end extensions C. A packing *a* of suitable material is inserted within the recess. Said rings are preferably provided with orifices *d* to adapt them to be operated by a spanner-wrench. Cones F are preferably provided with similar orifices.

L represents the axle.

Mode of operation: The cups D are first inserted in the sockets of extensions C, and then the sleeve E is inserted in the shell A, with one of the cones F in position. The balls on this end are then dropped in between the parts D and F. The cone F is then secured to the other end of the sleeve and the balls inserted, the cones turned to the desired adjustment, and the nuts H and washers *h* are turned to secure the parts in their adjustment, and packing-rings K are attached. The axle is then inserted through the frame-forks and through the sleeve E, and the forks clamped to the other end of the sleeve by the outside clamping-nuts I I', and the clamp-nuts I I' clamp the forks against the shoulders formed by the ends of the sleeve. It will readily be seen that the bearing can be readjusted by operating the cone F at one end of the sleeve only, which is a material saving in labor, and the parts can be taken apart and put together in a simple and convenient manner. The packing-rings protect the bearings and hold the oil therein in a superior manner. The method of clamping the frame and axle to the sleeve is also a great advantage, allowing the wheel to be detached from the axle and frame without disturbing the bearings.

Having described our invention, we claim—

In a bearing for bicycle-wheels, the combination of a hub-shell A, having outward and inward end extensions forming sockets, cups D seated within said sockets, a sleeve E screw-threaded at each end, cones on the screw-threaded portions of said sleeve, balls in-

serted between said cups and cones, clamp-nuts H, an axle detachably secured within said sleeve, annular packing-rings K screw-threaded on their outer faces to engage with threads on the inner surfaces of extensions C, said rings being recessed on their inner faces, and a packing in said recesses, substantially as specified.

In testimony whereof we have hereunto set our hands.

LLEWELLYN HENRY.
JAMES O. TEBOW.
